UNITED STATES PATENT OFFICE.

THOMAS SPENCER MILLER, OF SOUTH ORANGE, NEW JERSEY.

CONVEYING APPARATUS.

No. 874,223.

Specification of Letters Patent.

Patented Dec. 17, 1907.

Application filed December 14, 1904. Serial No. 236,851.

To all whom it may concern:

Be it known that I, THOMAS SPENCER MILLER, a citizen of the United States, and a resident of South Orange, Essex county, and 5 State of New Jersey, have invented a new and useful Improvement in Conveying Apparatus, of which the following is a specification.

In my application No. 45432 filed January 31, 1901, I have described a cableway 10 primarily intended for conveying loads over the water between a towing and a towed ship.

One object of my present invention is to better adapt said apparatus to the conveyance of loads from ship to shore or vice versa, 15 although certain features of my present invention will be applicable to other purposes.

In the accompanying drawings, Figure 1 is a side view of a form of apparatus in which I at present prefer to embody my invention. 20 Fig. 2 is a top view of a portion thereof. Fig. 3 is a rear view of the shore tower and tension device. Fig. 4 is a top view of the rope-drum-engine. Fig. 5 is a detail thereof.

1 and 2 are two load rests separated by a 25 gap 3. Cableway supports 4 and 5 are erected, respectively, on said load rests. A supporting cable 6 is stretched across said gap between said supports and a load carriage 7 runs on said cable provided with a 30 suitable hook upon which to hang the load. A traction rope 8^a 8^b is stretched parallel with said cable across said gap between said supports and back again, forming a traction engagement with the carriage 7. A tension 35 device 9 operates upon the ropeway to prevent the sagging of the load-carriage. A depressor 10 operates upon the ropeway above the load rest 2 to deflect the ropeway toward said load rest until the load rests 40 upon said load rest and can be unhooked from the carriage, as shown in dotted lines in Fig. 1. The ends of the traction rope and the depressor rope are operated, respectively, by the drums 11, 12, and 13, which are driven 45 by engine 14 and are so controlled as to afford the actuation of said ropes under the various conditions hereinafter described. A support affording a running engagement which is shown at 15 is interposed between 50 one of the supports and the cableway to admit of relative movement between the same. A stationary anchorage 16 is provided for one end of the cableway; the other end of which is connected with the tension mech-

anism 9. The cableway is made divisible at 55 46 and is supported from the head support by a hoist 42.

In the specific application of my invention shown in the drawings, the gap is between the shore and a vessel anchored broadside to 60 the shore; the head load rest being the deck of the vessel and the tail load rest being the shore. The head cableway support 4 is the mast or rigging of the vessel, and the tail support 5 is a tower erected on the shore. The 65 cableway extends from the anchorage 16 seaward of the vessel, over the vessel and over suitable sheaves on the support 5 to the suspended weight 9 to which its other end is made fast. The run 8^a of the traction-rope 70 extends from its point of attachment to the load carriage 7 around the sheave 17, back again and between guide sheaves on the carriage 7, over a suitable sheave on the cableway support 5 to the rope drum 12 to which 75 its end is secured. The run 8^b of the traction rope extends from its point of attachment to the load carriage, over suitable sheaves on the cableway support 5, thence under the sheave 18 on the weight 9, thence 80 over suitable sheaves on the support 5 and down to the rope drum 13 to which its end is secured. The weight 9 thus acts as a tension device upon both the cable 6 and the traction rope 8^a, 8^b. The engine 14 is of the 85 reversible-link motion class and drives the drum shafts 23 and 24. The drums 12 and 13 run loosely on the shaft 23 and the ends of the traction rope are inversely wound thereon. A bolt or latch 25 operated by a hand 90 lever 26 enables the operator to connect these two drums so that they move as a unit or to disconnect the same, so that they move independently. They are respectively provided with independently operated friction 95 brakes 27 and 28 and one of them is provided with a clutch 29 controlled by a hand device 30 whereby the operator may frictionally connect or disconnect the drum 12 and the shaft 23 at will. For further details of the 100 drums 12 and 13, I refer to my Patent No. 761089, dated May 31, 1904. They may be revolved together in either direction by the engine or they may be permitted to run together loose in either direction, or the drum 12 may be driven in either direction while the drum 13 is either held by its brake 28 or 105 permitted to run loose. The depressor drum

11 runs loosely on the shaft 24 by which it may be frictionally driven through the clutch 31 controlled by the hand device 32. The depressor drum 11 is also controlled by 5 the foot-operated friction-brake 33 and is connected with the depressor 10 by the rope 34 extending under the sheave 35 at the tail load rest.

The depressor consists of a block secured 10 to the end of the rope 34, in which block are mounted the sheaves 36, 37 and 38 engaging, respectively, the cable and the two runs of the traction rope so as to be adapted to deflect the whole in unison toward the tail load 15 rest 2, as shown in dotted lines in Fig. 1.

The support 15 which affords the running engagement consists of a block through which run the ropes 6 and 8^a on the sheaves 20 39, 40, and 41. This block is suspended from the rigging of the ship by the fall-rope 42 operated by the power-driven-drum 43 on the ship. It will be observed that this block suspends the two branches of the traction rope 8^a and the cable 6 at a point between 25 the traction rope sheave 17 and the load carriage so that the block has ample scope for running back and forth upon the traction rope as the vessel is moved by the waves without conflicting with the sheave 30 17. The block of the traction rope sheave 17 is provided with a suspending trolley 44 running upon the cable 6 and is held in distended position by the rope 45 connecting said block with the anchorage 16.

35 The divisibility of the ropeway may be provided for as follows: A coupling 46 is placed in the cable 6 between the vessel and the seaward anchorage and another coupling 47 is placed in the rope 45. When the cable-way 40 is in operation, as in Fig. 1, rolling or lurching of the ship on the waves is permitted by the running engagement at support 15 without unduly straining the cable-way or the rigging. The yielding tension 9 45 holds the whole cableway taut while permitting it to be raised or lowered by either the block 15 or 10. The independent operativeness of the friction drums 12 and 13 at opposite ends of the traction rope enables 50 the rope to be adjusted to the proper length for moving the load carriage before the drums are bolted together and also enables the traction rope to be hauled in when the ship departs. The proximity to each other 55 of the levers controlling the three rope drums 11, 12 and 13, enables the operator to control the proper relationship between the transit movement of the carriage and the delivery movement or depression of the cableway 60 toward the tail load rest. After the transportation of the load is complete, the carriage is first hauled in to haul down 10, the running supporting block 15 is lowered to the deck of the vessel and detached from its 65 supporting rope 42. Then the coupling 47

is detached and the drums 13 and 12 unbolted from each other. Thereupon, by applying a brake to the drum 13 which will keep carriage up over 2 and the friction clutch to the drum 12 and running the engine 70 in a direction to wind in on drum 12, the traction rope is hauled in bringing with it the sheave 17, the running supporting block 15, which are run in on the cable 6 until they are collected above the load rest 2. Then the 75 supporting cable 6 is uncoupled at 46 and the ends on opposite sides of the coupling may be secured to buoys and dropped into the sea on opposite sides of the ship, which is then free to depart. On the return of the ship, the 80 buoyed ends of the cable are picked up and one of them is passed over the ship and recoupled to the other. The tail sheave 17 is then run out on the cable and recoupled to the rope 45. The running supporting block 85 15 is then run out and made fast to its suspending rope 42 whereupon the apparatus is in condition to operate.

Although I have described the apparatus as transporting the loads from the vessel to 90 the shore, it may be used in the reverse direction for transporting from the shore to the vessel, in which case the head rest would, of course, become the tail rest and the tail rest the head rest. 95

Having thus described my invention, what I claim as new and desire to secure by Letters Patent:

1. In combination, a traction rope extending from the shore over and beyond a vessel, 100 an anchorage seaward of the vessel whereby said traction rope is held distended, a load carriage operated by said traction rope and a support for said traction rope on the vessel between the load carriage and the seaward 105 end of said traction rope.

2. In combination, a traction rope extending from the shore over and beyond a vessel and back again, a sheave in the seaward loop of said traction rope, an anchorage to which 110 said sheave is secured, a load carriage operated by said traction-rope and a support on the vessel for said traction rope between the load carriage and sheave.

3. In combination, a traction rope extending from the shore over and beyond a vessel and back again, two friction drums with which the opposite ends of said traction rope are connected, a sheave in the seaward loop of said traction rope, an anchorage to which 115 said sheave is connected and a support on the ship for said traction rope between said load carriage and sheave. 120

4. In combination a carrying cable extending from a stationary anchorage over a 125 vessel to an anchorage seaward therefrom, a flexibly mounted support on the vessel forming a running engagement with said carrying cable, and a load carriage on said carrying cable. 130

5. In combination, a carrying cable extending from the shore over a vessel to an anchorage seaward therefrom, a traction rope extending from the shore over and beyond said vessel and connected with said anchorage and a support on said vessel forming a running engagement with both said cable and traction ropes and a load carriage operated on said cable by said traction rope.
- 10 6. In combination, a traction rope extending from the shore over and beyond a vessel, a seaward anchorage whereby said traction rope is held distended, a support on the vessel forming a running engagement with said traction rope and a load carriage operated by said traction rope.
- 15 7. In combination, a carrying cable extending from the shore over a vessel to an anchorage seaward thereof, a traction rope extending from the shore outward to said vessel, two drums operating, respectively, on the opposite ends of said traction rope, a sheave in the seaward loop of said traction rope, a trolley supporting said sheave on said carrying cable and a load carriage running upon said carrying cable and operated by said traction rope.
- 20 8. In combination, a carrying cable and a traction rope extending from the shore over and beyond a vessel, an anchorage for the seaward ends of the same and a yielding tension device for said carrying cable.
- 25 9. In combination, a carrying cable, a traction rope extending from the shore over and beyond a vessel, an anchorage for the seaward ends thereof and a yielding tension device for both said carrying cable and said traction rope.
- 30 10. In combination, a carrying cable and a traction rope extending from the shore to a vessel, a counterweight for the cable an anchorage for the seaward ends thereof, a support therefor on said vessel, a load carriage, a load landing and a depressor arranged to exert a downward pull upon the cable and the traction rope whereby the load is brought down to said landing.
- 35 11. In combination, two load rests on opposite sides of a gap, cableway supports erected upon said rests, a cableway extending between said supports, a counterweight for the cable a load carriage thereon, a traction rope, a cableway depressor arranged to exert a downward pull upon the cableway and an engine containing drums which operate, respectively, said traction rope and said depressor.
- 40 12. In combination, two load rests on opposite sides of the gap, cableway supports erected upon said load rests, a cableway between said supports, a counterweight for said cable a hoist whereby said cableway is suspended from one of said supports so as to be raised or lowered above the load rest adjacent thereto and a depressor arranged to exert a downward pull on the cableway above the other load rest to assist in delivering the load thereon.
- 45 13. In combination, a cableway extended over a vessel between anchorages on opposite sides thereof, a counterweight for said cable, and a running connection between said vessel and said cableway whereby said cableway is freed from the movements of said vessel.
- 50 14. In combination, a cableway extended over a vessel between anchorages on opposite sides thereof, a running block on said cableway and a hoist whereby said block is suspended on said vessel.
- 55 15. In a conveying and loading apparatus, the combination with a vessel and an anchorage, a cableway secured to the anchorage and connected to and passing over the vessel in a manner to permit the free movement of the latter, a counterweight for said cable a carriage on the cableway, a traction rope, and a unitary tension device for the cable and the traction rope.
- 60 16. In a conveying and loading apparatus, the combination with a vessel and a stationary anchorage, of suspending means carried by the vessel, a cableway supported from and movable relative to said suspending means, means for raising and lowering the suspending means, and a traveling carriage for the cableway.
- 65 17. In a conveying and loading apparatus, the combination of a vessel, an anchorage, a counterweighted conveyer track or way extending between the anchorage and the vessel, and yieldingly supported from the latter, a carriage on said way, means for raising and lowering the way adjacent to the stationary anchorage, and means for raising and lowering the way at its point of support on the vessel.
- 70 18. In a conveying and loading apparatus, the combination of a vessel, a stationary anchorage, a counterweighted conveyer track or way extending from the stationary anchorage to a point beyond the vessel; said track or way being normally connected to the vessel at a point a relatively high distance above the deck of the latter, a carriage adapted to travel on the way, and means for raising and lowering the conveyer track or way adjacent to the stationary anchorage, and a tension device for such track or way.
- 75 19. In a conveying and loading apparatus, the combination with a vessel and a stationary anchorage, a carrier cable extending from the stationary anchorage to a point beyond the vessel, a pulley support for the cable at a point above the deck of the vessel, an endless conveying cable extending from the stationary anchorage to a point beyond the vessel and also supported by the pulley, means for raising and lowering said pulley, and a carriage driven by said conveying cable.

20. In a conveying and loading apparatus, the combination with a vessel, and a tower, a carrier cable extending from the tower to a point beyond the vessel, an endless conveying cable extending from the tower to a point beyond the vessel, a weight for the shore end of the carrier cable, a pulley support for the cables at a point above the deck of the vessel, means for raising and lowering the cables and 10 an engine for driving the conveyer cable.

21. In a conveying and loading apparatus, the combination with a vessel and a tower, of a carrying cable extending from the tower to a point beyond the vessel, an endless conveying cable extending from the tower to a point beyond the vessel, means for supporting said 15

cables from the vessel, a cable coupled to the outer end of the carrier cable, a tension cable connected to the endless conveyer cable, and a carriage traveling along said carrier cable. 20

22. In combination, a cableway, a take-up and pay-out mechanism connected with one end thereof, and a haul-down rope having a running connection with said cableway adjacent to said end. 25

In testimony whereof, I have hereunto signed my name in the presence of two subscribing witnesses.

THOMAS SPENCER MILLER.
